CUT-OFF MACHINE FOR METAL STOCK

Stanley J. Burwell, Plainfield, N. J., assignor, by mesne assignments, to Rockwell Manufacturing Company, a corporation of Pennsylvania

Application October 17, 1955, Serial No. 38,409

Term of patent 14 years

(Cl. D54—14)

Fig. 1

Fig. 2

*Fig. 3**Fig. 4*Figure 1 is a perspective view of a cut-off machine for metal stock, embodying my new design, showing the front and right side of the machine;

Figure 2 is a plan view of the cut-off machine for metal stock shown in Figure 1;

Figure 3 is a perspective view of the cut-off machine for metal stock shown in Figure 1, showing the rear and left side; and,

Figure 4 is a front elevational view of the cut-off machine for metal stock shown in Figure 1.

I claim:

The ornamental design for a cut-off machine for metal stock substantially as shown.
